UNITED STATES PATENT OFFICE

CLIFFORD A. CUTLER, OF BUFFALO, NEW YORK

METHOD OF AND APPARATUS FOR DRYING LUMBER

Application filed January 14, 1925. Serial No. 2,274.

My invention relates to kilns for drying lumber, and particularly to a kiln for drying lumber which is piled on edge.

The principal object of my invention has been to provide a method and means of drying lumber which shall perform the operation in a very efficient and uniform manner.

My invention relates not only to a new and useful method of drying lumber, but also to the construction of a kiln for carrying out my method.

The above objects and advantages have been accomplished by the device shown in the accompanying drawings, which is a preferred form of apparatus for carrying out my method.

In the drawings:

Fig. 1 is a front sectional elevation of one of my kilns.

Fig. 2 is a sectional plan view of a series of kilns, built adjacent each other, showing portions of the kilns broken away.

Fig. 3 is a fragmentary, sectional side elevation of one of my kilns, taken on line 3-3 of Fig. 1.

Fig. 4 is a front sectional elevation of a modified form of kiln.

As indicated above, I have shown in Fig. 2, a series of kiln chambers 5 arranged adjacent each other and under one roof. Each of the kiln chambers is provided with a bottom floor 6 and with an interspaced false floor 7. Supporting walls 8, 9, 10, and 11 are provided, which serve not only to support the false floor 7, but serve also to provide a suction duct 12 and discharge ducts 13 and 14. The walls 8 and 11 are interspaced from the sides 15 and 16, respectively, of the kiln thus providing compartments 17 and 18, respectively. The upper side of the compartments 17 and 18 are exposed to the interior of the kiln chamber 5, and a series of openings 19 is provided in each of the walls 8 and 11, which openings connect the discharge ducts 13 and 14 with the compartments 17 and 18, respectively, and in which a plurality of louvers 35 may be arranged. 20 represents the pile of lumber, each piece being set on edge and the whole pile being carried by a truck 21 which is supported by tracks 22,

mounted upon the false floor. The pile 20 is of such a size that spaces will be provided entirely around the pile for the circulation of air. The pieces of lumber are preferably separated vertically so as to provide vertical circulation of the air.

Each of the kiln chambers is provided with suitable means for sucking the air from the suction duct 12, and forcing it into the discharge ducts 13 and 14. This means may comprise a blower 25 and 26 arranged in front of the discharge ducts 13 and 14, respectively, and each having its discharge end 27 connected with a discharge duct. The suction sides 28 of the blowers are preferably connected together in one Y-shaped fitting 29, which is connected with the suction duct 12. Formed in the false floor 7, and arranged centrally above the suction duct 12, is a suction opening 30, whereby the moisture-laden air coming from the lumber will be drawn into the suction duct and thence to the blowers. This opening 30 is preferably tapered, having its wider part at the rear end of the duct, where the suction is less, whereby there will be a uniform distribution of suction throughout the length of the drying chamber. It is obvious that a blower unit will be provided for each of the kiln chambers 5 but for clearness of illustration, I have shown but one of these chambers.

Arranged in the compartments 17 and 18 is a series of heaters 31 by which the air as it comes from the openings 19 will be heated in its passage upwardly into the kiln chamber.

In the form of device shown in Fig. 4, heaters 32 are arranged within the kiln chamber and preferably along each of the side walls thereof. Carried at each side of the pile of lumber is a deflection wall 33, which extend up into the chamber a considerable distance so as to direct the incoming air from compartments 17 and 18 up along the side walls of the chamber and over the heaters 32. So as to prevent the air being drawn directly through the central portion of the pile of lumber, I sometimes provide a baffle plate 34 over the suction opening 30, formed in the false floor, so that if necessary the suction of the air currents

will be more evenly distributed throughout the pile of lumber.

In carrying out the method by the apparatus herein shown and described, it will be obvious that as the air is forced by the blowers 25 and 26 into the discharge ducts 13 and 14, it will pass through the openings 19 in the walls 8 and 11 and thence into and through the compartments 17 and 18. The air in passing through the compartments 17 and 18 is heated and blown upwardly along the side walls of the kiln, where it is deflected downwardly through the vertical passageways formed in the pile of lumber. Suction is also produced in the duct 12 by the blowers, and the air after it has been circulated through the lumber is drawn into this duct through the opening 30, and again recirculated through the drying chamber. However, not all of the air will be recirculated, since, during the drying process, the moisture is changed to vapor which causes some moisture-laden air to pass out of the kiln through the chimneys thereof.

The operation of the form shown in Fig. 4 is identical with that just above described, except that the air is heated in its passage upwardly along the side walls of the kiln chamber instead of in the compartments 17 and 18. Air from the drying chamber is drawn out through the opening 30, but greater distribution of air currents through the pile of lumber is brought about by the provision of the baffle plate 34.

Obviously some other modifications of the details herein shown and described may be made without departing from the spirit of my invention, or the scope of the appended claims, and I do not, therefore, wish to be limited to the exact embodiment herein shown and described, the form shown being merely the preferred form thereof.

Having thus described my invention, what I claim is:

1. A lumber drying kiln comprising a chamber having a trackway extending lengthwise thereof and adapted to receive lumber carrying trucks, a suction duct located below the rails, a discharge duct at each side of the suction duct, a compartment at one side of each of the discharge ducts, the wall between each discharge duct and adjacent compartment being formed with openings, air reheating means, and means for withdrawing air from the kiln through the suction duct, passing it through the discharge ducts and into the compartments, and then discharging it upwardly into the kiln and bringing it in contact with the heating means.

2. A lumber drying kiln comprising a chamber having a bottom floor, a false floor in interspaced relation with the bottom floor, walls connecting the floors and forming a suction duct and a discharge duct on each side of the suction duct, the false floor being

provided over the suction duct with a graduated opening, the chamber being also formed with a compartment at one side of each of the discharge ducts, the walls separating the discharge ducts and the compartments being formed with a plurality of openings, deflector walls carried by the false floor and arranged one at each side of the lumber carrying trucks, a baffle plate arranged over the graduated opening communicating with the suction duct, tracks extending lengthwise of the chamber and adapted to receive lumber carrying trucks, air reheating means, and means for withdrawing air from the kiln through the suction duct, passing it through the discharge ducts and into the compartments, and then discharging it upwardly into the kiln and through the reheating means.

In testimony whereof, I have hereunto signed my name.

CLIFFORD A. CUTLER.
